UNITED STATES PATENT OFFICE

2,668,410

COTTON PICKING MEANS

John J. Bramblett, Pine Bluff, Ark., assignor to
 Ben Pearson, Incorporated, Pine Bluff, Ark., a
 corporation of Arkansas

Application September 8, 1952, Serial No. 308,335

13 Claims. (Cl. 56—44)

1

This invention relates to certain new and useful improvements in cotton picking machines, and particularly relates to a picking machine of the so-called spindle type in which a plurality of spindles are mounted in vertical banks and provided with rotating means, the rotating spindles being moved into and out of a picking zone in which they come into contact with the cotton carried by cotton plants and effect removal of the lint from the bolls.

More specifically this invention relates to an improvement in spindle means for use with such cotton picking machines and in means for operating such spindles. The use of tapered spindles having barbs for the purpose of more efficiently engaging the cotton carried by the plants has heretofore been known. It has further heretofore been contemplated that barbs might be employed in a cotton picking spindle and retracted out of picking relation so as to provide for stripping the picked cotton from the spindle.

The principal object of the present invention is to provide an improved construction for a toothed picking spindle so as to accurately and efficiently provide for advancement of a shell relative to the teeth of the picking surface of the spindle to strip the picked cotton from the teeth.

A further object of the invention is to provide a spindle for a cotton picking machine which comprises a core for mounting in the picking machine for travel in a fixed path and a shell surrounding a portion of the core and reciprocable relative thereto, in which the shell is connected to the core through a resilient connection.

A further object is to provide such a fixed core with serrations or teeth and to provide such shell with slots through which the serrations normally project.

A further object is to provide such a spindle in which both the serrated or toothed portion of the core and the shell taper toward the outer end of the spindle.

A further object is to provide in a cotton picking machine a plurality of such spindles and cam means arranged in the path of travel of the spindles and effective to advance the shells outwardly from the spindles so as to move the shell surface into engagement with the tooth engaged cotton and to remove the cotton from the teeth so that it may be easily removed from the spindle subsequently.

A further object is to provide a cotton picking spindle consisting of a core and a shell slidable on the core in which the core is provided with a plurality of rigidly fixed longitudinally extending

2

blade-like members respectively having serrated, sawtooth edges and the shell is slotted to accommodate such blade-like members.

A further object of the invention is to generally improve the design, construction and efficiency of operation of picking spindles for cotton picking machines.

The means by which the foregoing and other objects of the present invention are accomplished and the manner of their accomplishment will readily be understood from the accompanying drawings, in which:

Fig. 1 is a fragmentary top plan view of a cotton picking machine forming a portion of a cotton picker, and illustrating the general environment of the invention.

Fig. 2 is a fragmentary sectional elevation taken as on the line II—II of Fig. 1.

Fig. 3 is a fragmentary sectional plan view on an enlarged scale taken as on the line III—III of Fig. 2.

Fig. 4 is a central longitudinal sectional view on a further enlarged scale of a single spindle made up in accordance with this invention, and in picking condition.

Fig. 5 is a transverse sectional view of a spindle in picking condition taken as on the line V—V of Fig. 4.

Fig. 6 is a transverse sectional view taken as on the line VI—VI of Fig. 4.

Fig. 7 is a transverse sectional view of a spindle in stripping condition on the scale of Fig. 5, taken as on the line VII—VII of Figs. 3 and 8; and

Fig. 8 is a view similar to Fig. 4 of a spindle in stripping condition.

Referring now to the drawings in which the various parts are indicated by numerals, the picking machine in which the present invention is embodied is shown as enclosed within a housing 11 and comprises a plurality of elongated box-like supporting members 13, each support 13 having fixed thereto a plurality of spindles 15. The box-like supports 13 are fixed to upper and lower heads 17, 18, with which they cooperate to form a drum by which the spindles are carried. The drum is fixed to a drive shaft 19, upon the upper end of which shaft is fixed a sheave 21, the sheave being driven as by a belt 23 from suitable drive means, not shown, for the purpose of revolving the drum.

Each of the supports 13 is provided with a spindle driving shaft 25, upon which driving shafts are carried a plurality of spindle drive gears 27 which are preferably bevel gears. Shafts 25 are preferably journaled respectively in the tops and bottoms of supports 13 and preferably project

above the tops of supports 13 and are provided with drive gears 29 which mesh with a bull gear 31 projecting upwardly beyond the top of housing 11 and having a sheave 33 secured thereto, the sheave 33 being connected as by a belt 35 to drive means, not shown, drive of the bull gear effecting drive of shafts 25 and of gears 27 carried thereby.

Each of the picking spindles 15 consists of an elongated core 37, which, for the purposes hereinafter pointed out, is preferably hollow from end to end providing a bore 38. At the inner end of core 37 a gear 39 of the bevel type is fixed. Outwardly from gear 39 core 37 is surrounded by a suitable bushing 41, upon which is journalled a journal portion 43, the journal portion at its inner end being threaded as at 45. Supports 13 are provided with a plurality of threaded bores into which the threaded portions 45 are threaded in order to mount the spindles upon the supports. When so mounted the spindle gears 39 project into the interior of supports 13 and into meshing drive engagement with the respective spindle drive gears 27, as shown in Fig. 2.

A collar 47 is fixed to core 37 at the outer end of journal 43 and is provided with a skirt 48 which is adapted to embrace the journal portion so as to limit outward movement of the journal portion relative to the core. Adjacent the outer end of the core and throughout a substantial portion of its length are carried a plurality of blade-like members 49, each of the blade-like members 49 being provided with a serrated saw tooth edge 51, or in the alternative, with a plurality of barbs or teeth. The blade-like members are rigidly fixed to the core 37 so as to radiate therefrom, and are disposed in alignment with and equally spaced about the longitudinal axis of the core with the saw-tooth edges 51 facing away from the core. The blades narrow toward their outer ends, so as to provide a uniform taper along their edges.

Slidably mounted on the core 37 is a hollow shell 53 which is preferably polygonal in cross section, being shown in the preferred embodiment as of substantially square cross section. Shell 53 at its outer end is provided with a substantially pyramidal-shaped tip portion 55 which is internally threaded to receive and threadedly engage an elongated screw 57 in the manner hereinafter described. The body of shell 53 is provided with a plurality of longitudinal slots 59 which separate the body of the shell into segments 53A. Each of the slots is adapted to slidably receive and accommodate a serrated blade-like member 49 and the slots preferably extend from solid tip 55 inwardly throughout the remainder of the length of the shell. At the inner end shell 53 is provided with a ring 61 which surrounds the shell segments 53A and serves to retain the inner ends of the shell segments against separation, as well as a cam abutment as pointed out hereinafter. Shell 53 tapers toward its tip, uniformly and similar to the taper of blades 49, and the segments 53A are so dimensioned as to be of less thickness than the width of blades 49 to provide for the projection of edges 51 beyond the shell when the shell is mounted on the core in retracted position.

As heretofore stated, core 37 is preferably provided with a hollow bore 38 extending from end to end of the core to receive and house elongated screw 57. At its inner end the hollow bore 38 of the core is enlarged to form a chamber 63 which

is of a size and diameter to receive the head 65 of screw 57. The hollow bore 38 is concentric with the longitudinal axis of core 37 and enlarged chamber 63 is concentric with the bore and with the axis.

Interposed between screw head 65 and the base of bore chamber 63 is a compression spring 67 which surrounds the inner end of screw 57, bears against the base of chamber 63 and oppositely against screw head 65, and constantly urges screw 57 inwardly relative to the bore 38, thus constantly urging shell 53, the tip of which is threadedly engaged with screw 57, to move inwardly relative to core 37 into the position as illustrated in Fig. 4. It will be seen that compression spring 67 thus serves to resiliently retain the shell in retracted position, as shown in Fig. 4, and that the shell may be advanced outwardly along the core within the limits permitted by spring 67 in chamber 63, the shell and core assuming in such advanced position the position best shown in Figs. 3, 7 and 8 in which the shell has so advanced that the surface of the shell is substantially flush with the serrated blade edges 51.

In the assembly of the device the respective spindles 15 are mounted upon supports 13 by the threaded engagement of threaded portions 45 with the threaded bores formed in the supports 13, the spindles thus being turnably supported by journals 43 in the respective supports 13 with spindle gears 39 drivingly engaged by drive gears 27. The entire assembly, consisting of the supports and spindles carried thereby and the upper and lower drum heads 17, 18, is mounted within housing 11 upon shaft 19 and driven by belt 23 effecting revolution of the drum in the direction indicated by the arrows in Figs. 1 and 3. As the drum is thus revolved the spindles are moved into and out of a picking zone P in which the spindles project into the path of plants, along a row of which the device may be moved, and drum revolution moves spindles opposite from the picking zone into and out of a stripping zone S in which it is desirable to remove the picked cotton from the spindles. During drum revolution drive of bull gear 31 is effected through belt 35 and through the interengagement of bull gear 31 with spindle shaft drive gears 29, spindle drive shafts 25 are driven, and through the interengagement of gears 27 and spindle gears 39 rotation of spindles 15 is accomplished.

As is shown in Fig. 2, when spindles 15 are moved into picking zone P they are presented with toothed edges 51 projecting from slots 59 in shells 53 and the rotating spindles with the projecting toothed edges efficiently engage and remove lint cotton from plants with which the spindles come in contact with the picking zone. The spindles, with the engaged cotton thereon, are moved from the picking zone into the stripping zone S and in order to facilitate removal of the picked cotton from the spindles it is desirable to provide means for advancing shells 53 outwardly along cores 37 until the spindles have assumed substantially the position shown in Figs. 7 and 8, in which the tapering shells, being moved outwardly along and relative to the tapering cores, are moved to a position where the relatively smooth surfaces of the shells are substantially flush with the toothed edges, shell slots 59 being moved along blades 49 and effectively forcing cotton engaged upon edges 51 away from and off of the edges, loosening the cotton and facilitating its subsequent removal.

For the purpose of mechanically effecting such shell advancement it is preferred that cam bar means 69 be mounted in the picking zone S. Cam bars 69 are preferably arcuate and are arranged concentrically with drum shaft 19 and are supported by leaves 71 fixed to attachment brackets 73, brackets 73 being attached to the side wall of housing 11. Cam bars 69 are arranged in the path of movement of spindles 15 and are positioned to be successively engaged by the spindles substantially at the inner end of shells 53. Preferably each cam bar 69 is mounted so as to act on the spindles in two adjacent, vertically spaced rows, that is each cam bar 69 works upon a plurality of spindles, half being in each of said rows, simultaneously.

Cam bars 69 are each provided with an approach portion 75 which is positioned to enter between shell ring 61 and core collar 41. As can best be seen in Fig. 3, cam bars 69 enlarge from approach portions 75 to the full thickness of the cam bars, in the direction of movement of the spindles during drum revolution. As the spindles are advanced toward the cam bars, approach portions 75 enter between rings 61 and collars 41 effecting separation by moving shells 53 outwardly against the action of springs 67. This separation is continued and the shells further advanced outwardly as the spindles are moved along the cam bar on to the body portion of the cam bars. In this manner shells 53 are advanced outwardly along cores 43 in the stripping zone, loosening the picked cotton as heretofore set out, which may then be removed from the spindles as through a suitable exhaust, such as exhaust pipe 17, as by a fan or other means not shown.

After the spindles have thus been acted upon by cam bars 69, continued drum revolution moves the spindles beyond the end of the cam bars, which, it will be observed, in abrupt, releasing the separating effect of the cam bars upon the spindles, springs 67 being then effective to return the spindles to the picking condition in which the shells are retracted and the toothed edges 51 project therebeyond.

It will be understood that while it is preferred that the spindle shells be of polygonal cross section so as to be substantially pyramidal in shape, they may be of circular cross section so as to be substantially conical in shape without departing from this invention. It will be further understood that while the present invention has been shown and described in connection with a drum in which the spindles travel in a relatively fixed circular path, it is also applicable to drum type cotton picking machines in which the spindles travel in other fixed paths, such as for example that illustrated in Patent 2,140,631.

I claim:

1. Cotton picking spindle means adapted for mounting in a cotton picking machine, comprising an elongated core, a journal portion surrounding said core adjacent one end of the core and supporting the core for rotation, a plurality of uniformly tapering blades carried by said core in alinement with the longitudinal axis of the core, said blades each including a serrated edge and having an edge opposite said serrated edge seated on and rigidly fixed to said core, each said blade extending from a portion of said core intermediate the length of said core substantially to the other end of said core, said blades radiating from said core in substantially equally spaced relation about said core and tapering toward said

other end, a collar carried by said core adjacent said intermediate portion, a tapering shell of polygonal cross section slidably mounted on said core having a like plurality of elongated slots, said blades respectively being positioned in said slots, said shell having a ring adjacent said collar, an end tip adjacent said core other end, and being longitudinally shiftable relative to said core from a retracted position in which said tip substantially abuts said adjacent core end, said collar and said ring are in proximate relation, and said serrated blade edges project beyond the exterior surface of said shell to an advanced position in which said tip is spaced from said adjacent core end, said ring is spaced from said collar, and said shell surface is substantially flush with said serrated edges and return, an attachment member extending through the interior of said core substantially from end to end and detachably secured at one end to said shell tip, a compression spring abutting said core interior and said attachment member adjacent its other end urging said shell into said retracted position, said spring resisting shift of said shell to advanced position and urging return from advanced position.

2. Cotton picking spindle means adapted for mounting in a cotton picking machine, comprising an elongated core, a journal portion surrounding said core adjacent one end of the core and supporting the core for rotation, a plurality of uniformly tapering blades carried by said core in alinement with the longitudinal axis of the core, said blades each including a serrated edge and having an edge opposite said serrated edge seated on and rigidly fixed to said core, each said blade extending from a portion of said core intermediate the length of said core substantially to the other end of said core, said blades radiating from said core in substantially equally spaced relation about said core and tapering toward said other end, a similarly tapering shell slidably mounted on said core, having a like plurality of elongated slots, said blades respectively being positioned in said slots, said shell having an end tip adjacent said core other end and being longitudinally shiftable relative to said core from a retracted position in which said tip substantially abuts said adjacent core end and said serrated blade edges project beyond the exterior surface of said shell to an advanced position in which said tip is spaced from said adjacent core end and said shell surface is substantially flush with said serrated edges and return, an attachment member extending through the interior of said core substantially from end to end secured at one end to said shell tip, spring means, abutting said core interior and said attachment member adjacent its other end, urging said shell into said retracted position, said spring means resisting shift of said shell to advanced position and urging shell return from advanced position to retracted position.

3. Cotton picking spindle means adapted for mounting in a cotton picking machine, comprising an elongated core, means adjacent one end of the core supporting the core for rotation, a plurality of uniformly tapering blades carried by said core in alinement with the longitudinal axis of the core, said blades each including a serrated edge and having an edge opposite said serrated edge seated on and rigidly fixed to said core, each said blade extending from a portion of said core intermediate the length of said core substantially to the other end of said core, said blades radiating from said core in substantially

7
equally spaced relation about said core and tapering toward said other end, a similarly tapering shell slidably mounted on said core having a like plurality of elongated slots, said blades respectively being positioned in said slots, said shell being longitudinally shiftable relative to said core from a retracted position in which said shell substantially abuts said core other end and said serrated blade edges project beyond the exterior surface of said shell to an advanced position in which said shell surface is substantially flush with said serrated edges and return, an attachment member extending substantially from end to end through the interior of said core, one end of said member being secured to said shell beyond said core other end, spring means abutting said core interior and said member adjacent its other end urging said shell into said retracted position, said spring means resisting shift of said shell to advanced position and urging return from advanced position to retracted position.

4. Cotton picking spindle means adapted for mounting in a cotton picking machine, comprising an elongated core, means for supporting the core for rotation, a plurality of uniformly tapering blade-like members, said blade-like members each including a serrated edge and having an edge opposite said serrated edge seated on and rigidly fixed to said core, each said blade extending along a portion of the length of said core, a similarly tapering shell slidably mounted on said core having a like plurality of elongated slots, said blade members respectively being positioned in said slots, said shell being longitudinally shiftable relative to said core from a retracted position in which said serrated blade edges project beyond the exterior surface of said shell to an advanced position in which said shell surface is substantially flush with said serrated edges and return, means connecting said shell to said core and spring means carried by said core engaging said connecting means and urging said shell into said retracted position, said spring means resisting shift of said shell to advanced position and urging return from advanced position.

5. Cotton picking spindle means adapted for mounting in a cotton picking machine, comprising an elongated core, means for supporting the core for rotation, a plurality of uniformly tapering elongated blade-like members, each including a serrated edge, said members being rigidly fixed to and radiating from said core, a similarly tapering shell slidably mounted on said core having a like plurality of elongated slots, said blade members respectively being positioned in said slots, said shell being longitudinally shiftable relative to said core from a retracted position in which said serrated blade edges project beyond the exterior surface of said shell to an advanced position in which said shell surface is substantially flush with said serrated edges and return, and means resiliently connecting said shell to said core, urging said shell into said retracted position and urging return from advanced position.

6. Cotton picking spindle means adapted for mounting in a cotton picking machine, comprising an elongated core, a plurality of uniformly tapering elongated blade-like members, each including a serrated edge, said members being rigidly fixed to and radiating from said core, a similarly tapering shell slidably mounted on said core having a like plurality of elongated slots, said blade members respectively being positioned in

5 said slots, said shell being longitudinally shiftable relative to said core from a retracted position in which said serrated blade edges project beyond the exterior surface of said shell to an advanced position in which said shell surface is substantially flush with said serrated edges and return, and means resiliently connecting said shell to said core, urging said shell into said retracted position, resisting shift of said shell to advanced position and urging return from advanced position.

7. A cotton picking machine which comprises a housing, a revolvable drum mounted in said housing, a plurality of substantially horizontal rotatable spindle cores secured in vertical banks to and radially projecting from said drum, said cores each having a plurality of blades, disposed and fixed longitudinally of the cores, having serrated edges remote from the core, a plurality 15 of spindle shells respectively slidably carried by and covering the radially outer portion of said cores remote from said drum means, said shells being slotted to receive said blades and being positioned on said cores with said blades in said slots, said blades and shells being uniformly tapered away from said drum means toward their outer ends, means, including spring means, resiliently coupling said shells to said cores and urging said shells inwardly along said cores to 20 a retracted position in which said serrated blade edges extend through said slots beyond the exterior of said shells, each said shell at its inner end being surrounded by an abutment ring, and each said core having a collar adjacent said 25 ring, a plurality of cam bars attached to said housing, each cam bar having a thin approach portion and a thick body portion and being supported between vertically adjacent spindle cores in the path of said rings during drum revolution, said approach portions entering between said 30 rings and collars to effect separation of said cores during drum revolution, cam shift of said shells moving said shells to an advanced position in which said serrated edges are substantially flush with said exterior surfaces, said resilient coupling means resisting said shift and effecting shell return to said retracted position upon departure from said bars, and means for revolving said drum means.

8. A cotton picking machine which comprises a housing, a revolvable drum mounted in said housing, a plurality of substantially horizontal rotatable spindle cores secured in vertical banks to and radially projecting from said drum, said cores each having a plurality of blades disposed and fixed longitudinally of the core and having serrated edges remote from the core, a plurality of spindle shells respectively slidably coupled to said cores and covering the radially outer portion of said cores remote from said drum means, said shells being slotted to receive said blades and being positioned on said cores with said blades in said slots, and said edges extended beyond the exterior of said shells, said blades and shells being uniformly tapered away from said drum means toward their outer ends, a plurality of cam bars attached to said housing, each cam bar having an approach portion and a body portion and being supported between vertically adjacent spindle cores in the path of the junction between said shells and said cores during drum revolution, said approach portions entering between said shells and cores to effect advancement of said shells relative to said cores and said body portion continuing said advancement 70 in 75

to effect shift of said shells outwardly relative to said cores during drum revolution, cam shift of said shells moving said shells to an advanced position in which said serrated edges are substantially flush with said exterior surfaces, and means for revolving said drum means.

9. In a cotton picking machine which comprises a housing, a revolvable drum mounted in said housing, and means for revolving said drum, a plurality of substantially horizontal rotatable spindles secured in vertical banks and radially projecting from said drum, said spindles each consisting of a serrated core and a shell slidably coupled on said core, with the core serrations projecting beyond the exterior surfaces of said shells, said spindles uniformly tapered away from said drum means toward their outer ends, and a plurality of cam bars attached to said housing, each cam bar having a thin approach portion and a thick body portion and being supported between vertically adjacent spindles, said approach portions entering between said cores and shells to effect advancement of said shells relative to said cores and said body portion continuing said advancement to effect shift of said shells outwardly relative to said cores during drum revolution, cam shift of said shells moving said shells to an advanced position in which said serrations are substantially flush with said exterior surfaces, whereby to disengage from said serrations cotton lint engaged thereon.

10. A cotton picking spindle comprising an elongated core having longitudinally alined serrations extending throughout a substantial portion of the length of the core, a shell slidably

30

mounted on the serrated portion of the core, said shell being of a length in excess of the length of said serrated portion, and attachment means resiliently coupling said shell to said core.

5. 11. A cotton picking spindle comprising an elongated core having longitudinally alined serrations extending throughout a substantial portion of the length of the core, a shell slidably mounted on the serrated portion of the core, and attachment means resiliently coupling said shell to said core.

12. In a cotton picking machine comprising a revolvable drum, a plurality of spindles mounted on said drum, said spindles each including a serrated core, a shell slidably mounted on the core and resilient means coupling said shell to said core, and cam means mounted in the path of said spindle shells during drum revolution, said cam means being effective to successively advance said shells relative to said cores against the action of said resilient means.

13. In a cotton picking machine comprising a revolvable drum, a plurality of spindles mounted on said drum, said spindles each including a tapered serrated core, a similarly tapered shell slidably mounted on the core and resilient means coupling said shell to said core, and cam means mounted in the path of said spindle shells during drum revolution, said cam means being effective to successively advance said shells relative to said cores against the action of said resilient means.

JOHN J. BRAMBLETT.
